UNITED STATES PATENT OFFICE.

DAVID FROELICH, OF BROOKLYN, NEW YORK.

AWNING BOX.

1,418,247.

Specification of Letters Patent. Patented May 30, 1922.

Application filed January 14, 1921. Serial No. 437,337.

To all whom it may concern:

Be it known that I, DAVID FROELICH, a citizen of the United States, and resident of the city of New York, borough of Brooklyn, in the county of Kings and State of New York, have invented a new and Improved Awning Box, of which the following is a full, clear, and exact description.

My invention relates to an awning box, 10 and aims to provide certain new and useful improvements in devices of this character.

It is well appreciated, that it is quite a common expedient to provide what is known as a key which co-operates with an awning 15 box to permit of the movement of the parts within the same when the hand crank is applied thereto.

This has been necessary, incident to the fact that the awning was liable to become 20 unrolled, aside from the fact that this lock serves to prevent unauthorized persons from actuating the mechanism.

This type of box has presented certain 25 defects, however, in that the key provided for unlocking the parts has quite often turned upon an actuation of the crank so that it has been necessary to stop this operation and readjust the key to again effect an unlocking of the parts.

With this objection in mind, I have 30 constructed an awning box, which shall utilize a key, insuring a positive unlocking of the parts, until the key is withdrawn, aside from the fact that the construction of the box 35 and locking mechanism as a whole, is greatly simplified.

A further object of my invention is the provision of means which will serve to guard 40 against the entry of any foreign substances, wilfully or accidentally introduced into the box.

Further objects of my invention will appear in the annexed specification and drawings, which latter present one practical embodiment of my invention, and in which;

Figure 1 is a plan view,

Figure 2 is a sectional view taken along the lines 2-2 of Figure 1, and in the direction of the arrows, and

Figure 3 is a sectional plan view taken along the lines 3-3, and in the direction of the arrows in Figure 2.

In these views the reference numeral 5 indicates the shaft to be turned, and which 55 extends into a box 6, and has secured to its lower end in the usual manner, a beveled

gear 7 for effecting a positive driving of this shaft.

It is to be noted, that a guide post 8 projects into the interior of the box 6, and may 60 conveniently serve as a bearing for the end of the shaft 5, as well as providing a key-hole opening 9, indicated in Figure 3, the purpose of which will hereinafter be more fully brought out.

Arranged within the boxing, and preferably in the space existent between the inner face of the guide post 8 and the same, is a dog presenting a tooth 10. This dog is in line with any of the teeth of the gear 7, and 70 normally extends between a pair of the same, a projection beyond this position being prevented by means of any suitable stops 11.

Thus a rotation on the part of the gear 75 is normally precluded, and a tendency to retain this position is imparted to the dog by any suitable means, such as springs 12 arranged upon stems 13, secured to the dog, and slidably associated with a plate or other 80 suitable member 14 secured to the boxing 6.

It is also to be noted that, the key hole opening 9 partially aligns with an opening 15 forming a part of the dog, even when the latter is in projected position. Thus it will 85 be seen that a key, preferably including a shank 16, a tapered outer end 17, and a key-way 18 will be capable of insertion through the key hole opening 9 into the opening 15, of the dog, and by virtue of the inclined 90 outer end of the shank 16, a further projection will result in a retraction on the part of the dog, it being also noted that the key way 18 co-operating with the key hole opening 10, will effectually preclude any movement of the key except by deliberate withdrawal.

From the foregoing it will be seen that the parts will now be in their unlocked position, and the end 19 of the hand crank or other element 20 with which the key is associated, will project into the corresponding socket 21 of the gear 22, meshing with the gear 7, thus permitting a turning of these elements.

Finally to provide means preventing the deliberate or accidental introduction of foreign particles into the box, I preferably utilize a cover 23 which is movably secured to the boxing 6, and serves in its normal position to cover the open end of the socket 21, and which may further be retained in

this position by means of any suitable lock 24.

Thus it will be seen that I have provided an awning box in which the parts are normally locked to prevent tampering with the same, these parts being capable of ready disengagement to permit of the actuation of the mechanism, and to insure against any accidental relocking of this mechanism.

10 Also an awning box constructed in accordance with my invention is extremely simple in construction, and may be placed upon the market at a very low figure, aside from the fact that the cover 23 may be utilized to advantage to guard against any foreign matter being inserted into the box.

Obviously numerous modifications of structure might readily be resorted to with-

out in the least departing from the spirit of my invention, which I claim as:

20

An awning box, including a driving member, a driven member, a dog adapted to engage one of said members, means for normally retaining said dog in projected position, a guide post, said guide post being 25 formed with a key hole, said dog being formed with an opening, and a key adapted to be inserted through said key hole opening and into the dog opening for retracting said dog, said key being formed with a 30 beveled outer end, and a key way secured to said key and co-operating with said key hole opening for preventing a rotation of the same.

DAVID FROEHLICH.
